UNITED STATES PATENT OFFICE.

ERNEST LOVE, OF PRINCE RUPERT, BRITISH COLUMBIA, CANADA.

TELEPHONE TRANSPOSITION SWITCHING BOX.

Application filed August 22, 1921. Serial No. 494,186.

To all whom it may concern:

Be it known that I, ERNEST LOVE, a subject of the King of Great Britain, residing at Prince Rupert, in the Province of British Columbia, Canada, have invented certain new and useful Improvements in Telephone Transposition Switching Boxes; and I do hereby declare that the following is a full, clear, and exact description of the invention, such as will enable others skilled in the art to which it appertains to make and use the same.

The present invention relates to a telephone transposition switching box.

The primary object of the invention is the provision of a device of the above specified character for use in transposing long distance telephone lines, either one or two pairs together, also what are known as phantom circuits and will do the work while conversations are going on over both pairs and also over the phantom circuit, all at the same time, and will cause no interruption to service, as the switching is instantaneous, thus allowing the telephone company to do all their transposing on lines, without taking them out of service, which results in the saving of both time and expense to the company using the device described in this application.

Another object of the invention is the provision of a device such as above referred to which allows the linemen to proceed with their work steadily all day irrespective of whether the lines are in use or not, and therefore permits of considerable more transposition work each day with an additional great saving to the company.

According to the old method of doing transposition work or work of this nature the transposition between pairs or between two pairs can only be made while the circuits are not in use, and before the linemen can proceed with the work it is necessary for the linemen to telephone to the wire chief of the exchange from which the work is started in order to find if the phantom circuit is in use. It can be plainly seen that this method causes considerable delay to the lineman and quite a loss to the company. This switching box eliminates this loss of time by permitting the linemen to continue with their work by simply connecting the apparatus to the wires, and proceeding in the usual manner.

This switching box can also be used for

changing transpositions from one type to another or for cutting transpositions out of circuits altogether.

Another object of the invention is the provision of a switch-box for the above mentioned purposes, which will be comparatively simple and inexpensive to manufacture, reliable and efficient in use, and readily operated.

With the above and other objects in view, the present invention resides in the novel features of construction, formations, combinations, and arrangements of parts to be hereinafter more fully described, claimed and illustrated in the accompanying drawing, forming a part of the present application; and in which,

Figure 1 is a diagrammatic view illustrating the wiring within the switching box;

Figure 2 is a view of the top plate of the box removed, showing the switches in side elevation;

Figure 3 is an end view thereof;

Figure 4 is a plan view of the box; and,

Figure 5 is a transverse sectional view taken therethrough.

Referring now to the accompanying drawings, by corresponding characters of reference throughout the several views, the numeral 6 designates in general my improved switching box, which as shown in the drawings for purpose of illustration, is of a substantially rectangular formation, comprising opposite side and end walls 8 and 9 connected at their lower edges by a bottom 10 and at their upper edges by a removable closure 11.

A series of binding posts 12 are positioned at the opposite ends of the box, and conductors 13 are connected thereto extending through openings formed in the box and being terminally equipped at their outer ends with clips 14 by means of which the said device can be connected to the various wires of the telephone system, as desired, or the like.

The top of closure 11 of the switching box is provided with a longitudinal opening 15 formed therein, in which is inserted, and held by means of fastening elements 16, a supporting plate 17.

This supporting plate 17 carries a series of switch elements 18 each of which comprises a supporting bracket 19 having insulating blocks 20 attached to the lower end thereof, between which are secured the spring

switch elements, 21, 22, 23, 24, 25 and 26 which are provided with contact points 27 adjacent their upper ends. These spring contact members 21 to 26 inclusive, are connected, as shown in Figure 1, by suitable conductors 28, to the before described binding posts 12 and to each other in a proper and desired manner.

The spring members 23 and 25 are extended above the remaining members 21, 22, 24 and 26, as shown in Figure 3, and have their upper ends engaged by the lower operating terminal 29 of an operating lever 30. Obviously when the lever is thrown in the various positions, as shown in the full and dotted lines in Figure 3, the different contact points 27 will be brought into engagement thus changing the circuit in the desired manner.

In use the clips 14 are connected to the desired conductors of the telephone system and the lever 30 operated after live wires have been cut in the desired manner to transpose the circuits so that the repairing or other work can be done, on the lines, without interfering with the ordinary talking circuits and thus permitting the transposing to be done, while conversation is carried on over the lines.

From the foregoing description taken in connection with the accompanying drawings, it will be manifest that a transposition switching box is provided which will fulfil all of the necessary requirements of such a device, and it should be understood in this connection, that various minor changes in the specific details of construction can be resorted to within the scope of the appended claims, without departing from the spirit

or sacrificing any of the advantages of the invention.

Having thus fully described the invention, what I claim as new and desire to secure by Letters Patent is:

1. The herein described device, comprising a box, binding posts at the ends of said box, conductors interconnecting the two sets of binding posts and switching elements in said conductors for transposing the circuits between the binding posts as and for the purposes set forth.

2. The herein described telephone transposition switching box including a housing, binding posts mounted therein and arranged in groups, switch elements mounted within the housing, conductors connecting the binding posts of one group to those of the other group by way of said switch elements, whereby when the switch elements are in various positions the circuit of the telephone system or the like to which the device is attached will be transposed.

3. The herein described telephone transposition switching box comprising a housing, binding posts mounted therein, conductors leading from the binding posts through the housing, attaching clips secured to the ends of the conductors, groups of separate switch elements mounted within the housing, conductors connecting these switch elements to the binding posts, and means for actuating the separate groups of switch elements independently for transposition of electric circuits to which the clips are attached.

In witness whereof I have hereunto set my hand.

ERNEST LOVE.
